(57) **CLAIM**

The ornamental design for a cushioning material for packaging, as shown and described.

DESCRIPTION

FIG. 1 is a top, front and right side perspective view of a cushioning material for packaging showing our new design, FIG. 2 is a front elevational view thereof, FIG. 3 is a rear elevational view thereof, FIG. 4 is a left side elevational view thereof the right side being a mirror image, FIG. 5 is a top plan view thereof, FIG. 6 is a bottom plan view thereof; and, FIG. 7 is a perspective view of a cushioning material for packaging showing our new design a set of them in packaging position, the packed sheet products and tying bands being shown in broken lines for illustrative purpose only and forms no part of the claimed design.
